UNITED STATES PATENT OFFICE.

MICHAEL KOHL, OF NORTH MILWAUKEE, WISCONSIN.

RIM SPREADER.

Application filed September 17, 1923. Serial No. 663,175.

To all whom it may concern:

Be it known that I, MICHAEL KOHL, a citizen of the United States, and resident of North Milwaukee, in the county of Milwaukee and State of Wisconsin, have invented certain new and useful Improvements in Rim Spreaders; and I do hereby declare that the following is a full, clear, and exact description thereof.

10 This invention relates to rim spreaders.

In rim spreaders as heretofore constructed, difficulty has been experienced due to the slipping of the parts along the rim and also due to the elaborate nature of the device 15 and the relatively extensive operations required to secure the correct functioning of such devices.

This invention is designed to overcome the above noted defects, and objects of such invention are to provide a rim spreader which may be readily clamped to any type of rim, which is cheaply constructed, which is compact and which is provided with means for pressing the nipple out of the way when the 25 device is used with certain types of rims.

Embodiments of the invention are shown in the accompanying drawings, in which:—

Figure 1 is a side elevation partly in section of one part of the rim spreader showing 30 the rim in its expanded position.

Figure 2 is a corresponding view of a slightly modified form showing the rim spreader in its contracted position.

Figure 3 is a large transverse sectional 35 view through the device.

The rim spreader is provided with clamping means at each end thereof which are of substantially similar construction. Therefore one only of such clamping means need 40 be described. This clamping means, as illustrated in an enlarged form, is shown in Figure 3, from which it will be seen that a pair of curved jaws 1 and 2 are provided, and that the lower portion of these jaws, as indicated at 3 and 4 are held in any suitable manner in sliding overlapping relation. For instance, plates 5 may be slotted and may guide the members 3 and 4. A set screw 6 may be provided which is passed 45 through the plates 5 and screwed into a threaded aperture in one of the members, as for instance, the member 4. A spindle 7 is provided with reversely threaded ends 8 and 9 which are screwed through the jaws 1 and 2. This spindle may have formed inte-

grally therewith a crank 10 to permit its ready rotation. The member thus far described is the left hand clamping member shown in Figures 1 and 2.

The right hand clamping member is of 60 substantially similar construction except that the plates 5' differ from the plates 5, such latter plates being provided with depending ears between which the portion 11 of the toggle link mechanism is received. 65 The other portion of the toggle link mechanism comprises a pair of levers 12 whose ends are pivotally joined to the plates 5 upon opposite sides thereof and to the portion 11 of the first mentioned link. It is to 70 be noted that the link 11 is provided with an extension 13 which is arranged angularly to the operative portion 11 thereof and forms a manipulating angularly arranged handle. 75

In using the device the clamping jaws are forced into engagement with opposed sections 14 and 15 of the rim, as shown in Figure 1. Thereafter, the operator presses downwardly upon the handle 13 and rocks it 80 into the position shown in Figure 2. In this position, it will be seen that the section 15 of the rim has been forced upwardly and caused to ride over the section 14 thereof. It may happen in certain types of 85 rims that the filling nipple for the tire extends downwardly through the section 15 adjacent the end thereof.

In this case a piece of strap iron 16 is pivotally mounted upon the spindle 7 of the 90 right hand clamping member and its free end is adapted to be positioned between the members 14 and 15 at the initiation of their sliding motion. This causes the flap 16 to be rocked upwardly thus pressing the filling 95 nipple upwardly and protecting it from damage from the adjacent end of the section 14 of the rim.

It is to be particularly noted that the device will not slip along the rim but may be 100 rigidly clamped thereto and that at all times during the manipulation of the rim spreader, the movement of the ends of the rim are under complete control.

It is further to be noted that the location 105 of the handle 13 is such that the operator may, with the greatest ease manipulate the device.

It will be seen that a rim spreader has been provided which may be constructed at 110

a minimum expense, which is effective in operation and which is of substantial and rugged construction.

Although a few forms of the invention 5 have been described in considerable detail, it is to be understood that the invention may be variously embodied and is, therefore, to be limited only as claimed.

I claim:

- 10 1. In a rim spreading device, the combination of pairs of jaws adapted to engage opposite sides of a rim, spindles having reversely threaded ends screwed into said jaws, cranks for rotating said spindle, a 15 plate associated with each pair of jaws, said plates being folded and cut away to receive said jaws, means carried by each of said plates for locking the plates to one of each of said jaws, a toggle link element pivoted 20 to each of said plates and pivoted to each other intermediate the ends of one of said elements, said last mentioned element having a manipulating extension projecting

outwardly at an angle to the remaining portion of said element.

2. In a rim spreading device, the combination of a pair of jaws adapted to engage opposite sides of a rim, spindles having reversely threaded ends screwed into said jaws, means for rotating said spindles, a 30 plate associated with each pair of said jaws, said plates being folded and cut away to receive said jaws, means carried by each of said plates for locking said plates to said jaws, a toggle lever mechanism having its 35 ends pivoted to said jaws and having one of its elements extended to form a separate handle, and a flap pivoted to one of said spindles and adapted to be inserted between the free ends of said rim prior to the expansion of said rim. 40

In testimony that I claim the foregoing I have hereunto set my hand at Milwaukee, in the county of Milwaukee and State of Wisconsin.

MICHAEL KOHL.
